UNITED STATES PATENT OFFICE

92,307

DESIGN FOR A PLATE OR SIMILAR ARTICLE

Karl Hippmann, Selb Bavaria, Germany, assignor to The Rosenthal China Corporation, New York, N. Y., a corporation of New York

Application September 22, 1933, Serial No. 49,317

Term of patent 7 years

To all whom it may concern:

Be it known that I, KARL HIPPmann, a citizen of Germany, residing in Selb Bavaria, Germany, have invented a new, original, and ornamental Design for a Plate or Similar Article, of which the following is a specification, reference being had to the accompanying drawing, forming a part thereof.

Fig. 1 is a top plan view of a fragment of a segment of a plate showing one repeat of my design.

Fig. 2 is a top plan view of a plate from which

the fragment of Fig. 1 is taken, the dot and dash lines *a*, *b* and *c* indicating the margins of the segment in which the design appears.

The design is repeated three times around the rim of the plate, once within each segment, there being a space between each design and within which a single leaf-spray design appears centrally of said space.

I claim:

The ornamental design for a plate or similar article as shown and described.

KARL HIPPmann.
